Jacob Resor, of Cincinnati, Ohio.
Letters Patent No. 1244, Dated May 15, 1860

The Schedule referred to in these Letters Patent, and making part of the same

To all whom it may concern:

Des. 1244

Be it known that J. Jacob Resor, of the City of Cincinnati, in the County of Hamilton, State of Ohio, have invented or produced a new and original design for Stove plates, and I do hereby declare that the following is a full and exact description of the same, reference being had to the accompanying drawing, Engraved.

The nature of the invention consists in arranging a series of curved ornamental elevations and depressions properly rounded off so as to give a very tasteful appearance to the Stove when it is put together.

Every panel or plate of the Stove is thus decorated with the exception of the portions employed for Cooking purposes and those parts not seen.

The panels are surrounded by a molding following the edge and shape of it and in this and on the panel the new decoration is found.

The design consists in a series of sinuous curves gradually increasing or diminishing in length to follow the shape of the panel or plate of which they form a part, and each of these curves are surrounded by an endless border, which follows their sinuosity, and they are separated from each other by slight depressions, and are rounded off at the ends. Each series of these curves, which form a panel on a plate, are surrounded by a simple border, horizontal on the top and bottom but curved at the sides in such a manner as to give the design on each tablet the appearance of an unrolled scroll.

The patterns have not their sinuosities relatively in the same direction on each plate, tablet or panel, but as will be seen by the plates A and B, the direction is reversed to make that have an elegant appearance, which would otherwise look monotonous.

The corners of the Stove, that is, those corners which have their line of junction vertical are not squared off but have a recess in them, in which another ornament, consisting of a pillar composed of rings alternately projecting and receding is placed. This corner has a castellated appearance. It is indicated by C.

Having thus fully described my invention what I claim is,

The design for Stove plates as above described, and illustrated in the accompanying drawing.
